UNITED STATES PATENT OFFICE.

ISRAEL KLAYMAN, OF BALTIMORE, MARYLAND, ASSIGNOR OF ONE-HALF TO BENJAMIN KLAYMAN, OF BALTIMORE, MARYLAND.

WINDOW-FRAME.

1,271,174.

Specification of Letters Patent.

Patented July 2, 1918.

Application filed January 9, 1918. Serial No. 211,092.

To all whom it may concern:

Be it known that I, ISRAEL KLAYMAN, a citizen of Russia, residing at Baltimore, in the State of Maryland, have invented certain new and useful Improvements in Window-Frames, of which the following is a specification.

The present invention relates to window frames and has for its purpose to provide a frame having movable portions which will readily allow of removing the window sashes and replacing the same in a simple and easily performed manner.

The invention is shown by way of illustration in the accompanying drawing wherein:

Figure 1 is a front elevational view thereof.

Fig. 2, a transverse sectional view on the line 2—2 of Fig. 1, and

Fig. 3, an enlarged sectional view showing the device for securing the front strip to the window frame.

Referring to the construction in further detail, the frame consists of a side portion 1, an outer and inner portion 2 and 3. A parting strip 4 is detachably secured in a groove of the portion 1, by spring tensioned bars 5 (one being shown). Each bar 5 fits 20 in a metal casing 6 and the tensioning spring 7 surrounds the bar 5 within said casing.

A hand engaging member 8 is carried by each bar 5 to withdraw said bar from engagement with a hook 9 carried by the removable strip 4. Said strip 4 thus provides the division piece which forms the two slideways for the window sashes.

A stop strip 10 is secured to the part 1 40 adjacent the portion 3 by means of bolts

11 (one being shown) each having a hooked end 12 adapted to engage in the aperture of a plate 13 secured to the part 1 as shown. The bolt 11 has an inner projecting portion 14 whereby said bolt may be readily depressed to disengage the locking elements 12 and 13. The bolt 14 is normally held under tension and in locked position by the spring 15, as shown.

The slot or opening in the plate 13 is 50 sufficiently large to allow of the hooked end of the bolt 11 being moved laterally when the stop strip 10 is to be removed. By this arrangement the hooked end 12 of the bolt 11 will easily clear said apertured plate 13. 55

It is obvious that those skilled in the art may vary the details of construction and arrangement of parts without departing from the spirit of my invention, and therefore I do not wish to be limited to such features 60 except as may be required by the claim.

Having thus described my said invention, what I claim as new and desire to secure by Letters Patent is:

The combination with a window frame, of 65 a stop strip disposed along one edge thereof, said window frame having an apertured plate covered by said stop strip, and a spring tensioned latch mounted on the stop strip having a hooked end engaging the 70 apertured plate and holding said stop strip in position thereon, substantially as set forth.

In testimony whereof I affix my signature in the presence of two witnesses.

ISRAEL KLAYMAN.

Witnesses:

NATHAN BLUMENTHAL,
JACOB B. GINSBURG.
